United States Patent Office

Des. 200,850

Patented Apr. 13, 1965

200,850

PORTABLE HIGH CHAIR OR SIMILAR ARTICLE

George Wm. Palmer, Van Nuys, and Sidney Shapiro, Los Angeles, Calif.; said Palmer assignor to said Shapiro

Filed Apr. 7, 1964, Ser. No. 79,389

Term of patent 14 years

(Cl. D15—1)

FIG. 1.

FIG. 2.

FIG. 3.

FIG. 4.

FIGURE 1 is a side elevational view of a design for a portable high chair or similar article showing my design, the dotted line showing of a table edge being for illustrative purposes only;

FIGURE 2 is a top elevational view of the portable high chair or similar article;

FIGURE 3 is a perspective view of the portable high chair or similar article; and

FIGURE 4 is a front elevational view taken from the right of FIGURE 1.

The dominant features of our design reside in those portions shown in full lines on the drawing.

We claim:

The ornamental design for a portable high chair or similar article, as shown and described.
